UNITED STATES PATENT OFFICE.

GEORGE R. STILLMAN, OF PHILADELPHIA, PENNSYLVANIA.

HYDROCARBON-LAMP.

SPECIFICATION forming part of Letters Patent No. 707,177, dated August 19, 1902.

Application filed April 24, 1902. Serial No. 104,441. (No model.)

To all whom it may concern:

Be it known that I, GEORGE R. STILLMAN, a citizen of the United States, residing at the city of Philadelphia, in the county of Philadelphia and State of Pennsylvania, have invented certain new and useful Improvements 5 in Hydrocarbon Lamps or Oil-Fonts, of which the following is a specification.

My invention has relation to that class of 10 hydrocarbon lamps or oil-fonts in which a portion of the font contains a filler of fibrous material, such as prepared wool, adapted to readily absorb the hydrocarbon oil, and thus prevent a splashing movement of the oil in the 15 oil-reservoir proper; and in such connection it relates to the particular construction and arrangement of the lamp or font.

The principal objects of my invention are, 20 first, to provide a reservoir or font for a hydrocarbon-lamp or similar structure with two chambers separated from each other by a perforated partition, the upper chamber adapted to receive fibrous material, such as prepared wool, and the lower chamber adapted 25 to receive the hydrocarbon oil, the upper chamber being traversed by a perforated wick-chamber, the lower open end of which communicates directly with the hydrocarbon-oil chamber; second, to extend the perforated 30 wick-tube beyond the oil reservoir or font and to surround the projecting end by a cap to form an overflow-chamber above the reservoir proper, and, third, to provide an oil reservoir or font of an inverted-frusto-conical 35 shape to prevent outflow of the hydrocarbon oil by overturning or tilting of the lamp.

The nature and scope of my invention will 40 be more fully understood from the following description, taken in connection with the accompanying drawings, forming part hereof, in which—

Figure 1 is a side elevational view of a hydrocarbon-oil lamp embodying main features of my invention. Fig. 2 is an enlarged vertical sectional view of the lamp, illustrating 45 the perforated partition and perforated tube carried by the same and the manner in which the oil reservoir or font of the lamp is divided into chambers or compartments. Fig. 3 is a horizontal sectional view, enlarged, of the oil reservoir or font; and Fig. 4 is a vertical sec-

tional view of the font, illustrating the same as resting on its inclined surface.

Referring to the drawings, A represents the oil-reservoir or font, preferably of an inverted-frusto-conical shape, having a flat bottom a' and a flat top a^2 . A certain distance above the flat bottom a' and parallel to the same is arranged a perforated partition or false bottom b , dividing the reservoir or font A into two chambers c and c' of preferably unequal size. The perforated partition or false bottom b also serves as a support for a centrally-arranged perforated tube b' , which extends through the flat top a^2 of the reservoir A and projects a certain distance above the same. The projecting end, b^2 of the perforated tube b' is surrounded by a cap or housing b^3 , which, in conjunction with the end, b^2 of said tube, forms an overflow-chamber c^3 above the reservoir A proper for a purpose to be hereinafter more fully explained. The cap or housing b^3 is provided with a downwardly-projecting threaded portion b^4 , into which the burner d , carrying the wick e and chimney f , is screwed. 75 The chamber c' is filled with a fibrous material, in the present instance with prepared wool, which is less liable to pack in said chamber, as is the case with cotton ordinarily used for such purpose. The lowermost chamber c , being separated by the partition or false bottom b of the reservoir A from the chamber c' , receives the hydrocarbon oil, which after having first completely filled said chamber rises into the upper chamber c' by readily passing 80 through the perforations b^5 thereof and is here absorbed by the prepared wool or other material. The overflow-chamber c^3 , however, remains normally empty and only receives oil when the lamp is tilted or overturned, as 85 illustrated in Fig. 4, in which instance said overflow-chamber c^3 by receiving the oil prevents an outflow of the same through the burner d and also prevents possible ignition of the hydrocarbon oil as well as explosion. 90 By first supplying the lowermost chamber c with oil through the perforated tube b' any impurities in the same will naturally accumulate and remain in the chamber c , even if the oil completely fills the chamber c and flows 95 into the chamber c' . The partition b , separating the chambers c and c' from each other,

will prevent the flow of any impurities into the chamber *c*' and onto and through the fibrous material thereof, so that the wool will always be kept cleanly and substantially free from such impurities of the oil. The connection of the perforated wick-tube *b*' directly with the lowermost chamber *c* affords ample room for the wick *e* by permitting the same to freely enter said chamber. This feature prevents the crowding and twisting, especially of a long wick *e*, in the perforated tube *b*' during insertion of the burner *d* onto the cap or housing *b*³, and, furthermore, permits the wick to maintain a substantially flat and straight position in the perforated tube *b*' and chamber *c*. The additional advantage of maintaining the wick in a flat position results in the proper feeding of the wick *e* to the burner *d* and also in the proper feeding of the oil to the flame through the wick.

Having thus described the nature and objects of my invention, what I claim as new, and desire to secure by Letters Patent, is—

1. A hydrocarbon lamp or oil font, compris-

ing a wick-chamber, the wall whereof is perforated, an oil-chamber arranged below the lower open end of said wick-chamber, a third chamber surrounding the perforated wall of said wick-chamber and arranged above the oil-chamber, the base of said third chamber being perforated, and a cap or housing arranged at the top of the font and adapted to surround and receive the upper open end of the wick-chamber.

2. A lamp-font, comprising an inverted-frusto-conical casing divided into upper and lower compartments by a horizontal perforated partition, and a perforated tube traversing the upper horizontal compartment and in open communication at its base with the lower compartment.

In testimony whereof I have hereunto set my signature in the presence of two subscribing witnesses.

GEO. R. STILLMAN.
